UNITED STATES PATENT OFFICE.

EDWARD F. LUKENS, OF WEST HAVEN, CONNECTICUT, ASSIGNOR TO THE NEW ENGLAND TUBE STAMPING COMPANY, INC., OF WEST HAVEN, CONNECTICUT, A CORPORATION.

WINDSHIELD CLEANER.

Application filed July 21, 1922. Serial No. 576,510.

To all whom it may concern:

Be it known that I, EDWARD F. LUKENS, a citizen of the United States, residing at West Haven, in the county of New Haven 5 and State of Connecticut, have invented a new and useful Improvement in Windshield Cleaners; and I do hereby declare the following, when taken in connection with the accompanying drawings and the characters 10 of reference marked thereon, to be a full, clear, and exact description of the same, and which said drawings constitute part of this application and represent, in—

Fig. 1 a view in inside elevation of a 15 wind-shield cleaner constructed in accordance with my invention.

Fig. 2 a view thereof in side elevation.

Fig. 3 a view thereof in transverse section on the line 3—3 of Fig. 2.

Fig. 4 a view corresponding to Fig. 3, 20 showing the device as applied to a wind-shield glass.

Fig. 5 a view of the device in central longitudinal section, also shown as applied to 25 a wind-shield glass.

My invention relates to an improvement in that class of wind-shield cleaners designed to simultaneously clean the opposite faces of a wind-shield glass, the object being to provide a simple, convenient, durable and effective device, constructed with particular reference to so closing when not in use as to protect the wiper-strips from injury.

With these ends in view, my invention 35 consists in a wind-shield cleaner having certain details of construction and combinations of parts as will be hereinafter pointed out in the claims.

In carrying out my invention, as herein 40 shown, I employ an inner wiper-member comprising a relatively deep, inwardly-opening, rectangular, trough-shaped, sheet-metal strip-holder 10 and a thick strip 11, preferably of felt, inserted thereinto, and projecting from the open face thereof, the strip 11 solidly filling the holder 10 and secured 45 therein by any suitable means. The said strip-holder 10 is pivotally hung about mid-way of its length on a transverse rivet 12 between the upper ends of the two parallel flanges 13 of a hollow, folded, sheet-metal hand-grip 14 permanently secured by rivets 15 to the offset end 16 of the inner arm 17 of a wiper-holder 18 made of a heavy strip 50 of spring metal, the said arm 16 of the

wiper-holder being inserted within the said hand-grip and riveted to the inner face of the outer portion thereof. As thus constructed, the inner strip-holder rocks within the hand-grip.

The outer wiper-member consists of a relatively flat, sheet-metal strip-holder 19, longer than the strip-holder 10 aforesaid and having its edges folded inward beyond the plane of its inner face, and then turned back beyond the plane of its outer face and then inward again to produce channels 20 for the reception of the outer edges of two flexible rubber wiper-strips 21 standing in planes at a right angle to the plane of the holder, and sufficiently separated from each other to receive between them the exposed portion of the felt strip 11 when the device is not in use, as shown in Figs. 1 to 3 inclusive, whereby the felt strip is enclosed between the strips 21 and protected thereby against injury and the accumulation of grit and dirt.

When the device is not in use, the face of the felt strip 11 rests upon the inner face of the flat, sheet-metal strip-holder 19, 70 as shown in Fig. 3, whereby the face of the felt strip is prevented from being fouled with grit or other foreign substances, and whereby the said strip-holder 19 acts as a stop-abutment to prevent the felt strip from 75 passing between, and protruding beyond, the rubber wiper-strips 21. This stop-abutment function of the part 19 also prevents the edges of the strips 21 from colliding with any part of the hand-grip 14, which would 80

endanger their deformation.

The strip-holder 19, by having its edges folded as described, has produced upon its outer face a shallow recess 22 for the flush reception of the outer arm 23 of the wiper-holder, this arm being permanently secured in place by rivets 24. By preference, and as shown, the outer edges of the rubber wiper strips 21 are thickened, so as to enable them to be readily clamped in place against 90 accidental withdrawal in use.

I do not, however, limit myself to the exact construction shown and described, my improved wind-shield cleaner being characterized by having its inner and outer wiper-members permanently attached to the respective arms of the wiper-holder and having the wiper-element of one member adapted to nest within the wiper elements of the other member, when the device is closed.

I claim:

1. In a wind-shield cleaner, the combination of a resilient holder, consisting of a single strip of spring-metal bent to form substantially parallel inner and outer arms; wiper-carrying members permanently mounted upon the respective arms of the said holder, one of the said members being pivoted to its arm and one member carrying a single thick strip of felt, and the other wiper-member carrying two flexible, rubber wiper-strips, spaced apart to receive the said strip of felt between them, and a web between the strips forming a stop-abutment therefor when the device is not in use.
2. In a wind-shield cleaner, the combination with a two-armed, resilient wiper-holder, consisting of a single strip of spring-metal bent to form substantially parallel arms, of which the inner arm is shorter

and offset; of a hollow hand-grip applied over the outer face of the said inner arm, to which it is permanently fastened, a trough-shaped strip-holder pivotally mounted in the said hand-grip, a thick wiper strip-mounted in the said strip-holder, a wiper-holder permanently attached to the inner face of the said outer arm, and two parallel wiper-strips respectively mounted in the edges of the said wiper-holder in planes at a right angle to the face of the said thick strip and spaced apart to receive the same between them when the device is not in use.

In testimony whereof, I have signed this specification in the presence of two subscribing witnesses.

EDWARD F. LUKENS.
